UNITED STATES PATENT OFFICE.

WILLIAM E. CHESTER, OF NORWOOD, OHIO.

REMOVABLE ARTIFICIAL DENTAL CROWN.

1,213,587.

Specification of Letters Patent.

Patented Jan. 23, 1917.

Application filed May 3, 1916. Serial No. 95,258.

To all whom it may concern:

Be it known that I, WILLIAM E. CHESTER, a citizen of the United States of America, and a resident of Norwood, in the county of 5 Hamilton and State of Ohio, have invented certain new and useful Improvements in Removable Artificial Dental Crowns, of which the following is a specification.

This invention relates to improvements in 10 artificial teeth, or, more particularly speaking, to removable or replaceable crowns, caps or facings for the roots of teeth that are left or retained in place and from which, as a rule, the nerves have been removed or otherwise deadened.

The objects of the invention herein will be 15 fully set forth in connection with the description of the details thereof that immediately follows that of the accompanying 20 sheet of drawings, in which latter,—

Figure 1 is a rear elevation showing the natural root of a tooth with a surmounted artificial crown or cap, the latter being in 25 removable-place according to my preferred form herein; Fig. 2, a vertical axial-section of Fig. 1, but on a slightly larger scale and showing my improved fastening connections between the tooth root and its artificial crown or cap; Fig. 3, a plan view of the 30 root, taken on the line *a*, *a*, of Fig. 2, but omitting the improved connecting post or pin that I use between the said root and the crown; Fig. 4, an elevation showing one 35 form of my improved doubly-shouldered connecting post or pin and omitting the boxing 40 therefor that is shown in Fig. 2; Fig. 5, a plan of the post seen in Fig. 4; Fig. 6, an elevation showing a modified form of the post or pin seen in Fig. 4; Fig. 7, a front 45 elevation of a wire frame or reinforce that is shown in the crown-portion of the tooth in Fig. 2, but with the crown-portion omitted; and Fig. 8, a plan view of the reinforce shown in Fig. 7.

It will be observed, before proceeding 50 further, that the several views of the drawings are made on an exceedingly exaggerated scale over and above the actual size of the several parts that form the essential features of the invention herein.

1 indicates the natural tooth root sur- 55 mounted by the crown or cap 2, the two being connected together by means of my preferred form of post or pin composed of a cylindrical body-portion 3 that has a lower,

tapered point 4, a head-portion 5 that has a flange 6 and a surmounting shouldered-part 7, the latter being of lesser diameter than the flange 6, and an upper, slightly tapered shank 9 of rectangular cross-section. 60 The base of shank 9 is of lesser diameter than the part 7 to produce a shoulder 10 on said part 7.

11 indicates the customary pulp or nerve canal of the root 1.

The upper part of the pulp-canal 11 is 65 suitably drilled out to produce the special form of seat or expanded, shouldered chamber in the upper end thereof, as best seen in Fig. 2, whereby a lower shoulder 16 is made 70 at the bottom of said seat and extends upwardly, and is screw-threaded as shown at 17, thence expands into a broad shoulder 18 having at its outer edge a groove 19, the face of the shoulder 18 being somewhat be- 75 low the upper face of the root 1. In this seat or countersunk-recess, made in the upper part of the pulp-canal, I provide a metallic box or bushing that has a body-portion 20 resting upon the grooved shoulder 18 and a lower, screw-threaded cylindrical-portion 21 that engages the shouldered, screw-threaded portion 16, 17 of said seat. 80 A tapered plug 22 is used in the said screw-threaded portion 17 of the box or bushing to 85 fasten the latter in place in said upper seat of the root. This bushing is intended to prevent the splitting of the root as well as to serve as a support for the said removable post. The internal diameter of said bush- 90 ing is made to coincide with that of the post 3, so that the latter can be inserted and tightly held therein and that it can be readily removed from the root when it is desired to get at the pulp-canal, down to the 95 bottom thereof, and even beyond, if necessary, for the treatment of abscesses or other ailments.

A lug or projection 23 is provided on the flange 6 and engages a notch 24 made in 100 the upper shouldered portion 25 of the bushing, as best shown in Figs. 2 and 3, a vertical screw 27 being inserted through a countersunk opening made in said lug 23 and adapted to engage a threaded hole made in 105 the body-portion of said bushing, whereby the post 3 can be securely held within said bushing against turning or accidental withdrawal, but detachable. Instead of using the said bushing the post 3 can be inserted 110

in the upper portion of the pulp-canal, after the latter has been duly prepared therefor, a shouldered recess being provided in the upper end or mouth of said pulp-canal, as shown in Figs. 4 and 6, to accommodate the flange-portion 6 its full depth, as seen in Fig. 4, or half the depth of the single-shouldered broad flange 7 seen in Fig. 6. In Fig. 4 the post 3 is shown as a plain one, while in Fig. 6 it is shown as a threaded one, the latter being adapted to engage a suitably threaded upper part of the pulp-canal for the due fastening thereof, while the plain post is preferably held in place by any easy drive-fit or a thin film of cement used therefor. The thin film used on the post 3 seen in Fig. 4 would not ordinarily be adhesive enough to prevent the removal of the post from the pulp-canal, because it is intended by me that the post can be removed by the dentist when it is desired to remove the crown or cap for any purpose and especially when it is necessary to get into the pulp-canal or at the base of the root.

If desired the lug 23 on the flange 6 and its recess 24 in the box can be dispensed with and the post held within the box or brushing by an internal thread in the latter, in which case the said post must be threaded, as shown in Fig. 6.

The crown or cap 2 is preferably held in place on the shank 9 in a detachable manner by means of a horizontal screw 29 whose inner end engages a seat made in said shank, as best shown in Fig. 2. The head of said screw 29 is made to seat flush with the inner face or lingual side of said crown and the threaded shank of the screw engages the internally threaded portion of a metal lining or bushing 30, at whose inner end a vertical, cylindrical member 31 is provided to engage over said shank 9, with its lower end resting on the shouldered portion 7 of the post, whereby the crown is securely held on said post with its base resting in true and flush contact with the upper dressed face of the root 1, entirely free from vibration, rocking, or wabbling. The shank 9 of the post may be made either tapering or straight, as desired.

In order to preserve the artificial or porcelain crown 2 from fracturing or breaking under ordinary conditions, I provide a reinforcing skeleton-frame that is embedded within the porcelain or material of said crown, as best shown in Fig. 2, but the reinforce is well shown in Figs. 7 and 8, wherein 32, 32 indicate vertical strips or bars, and 33, 34 indicate transverse strips or bars that are made of wire and somewhat roughened for better embedding-engagement with the substance of said crown.

It will be observed in Fig. 4 that the shank 9 is a tapered and angular one, while in Fig. 6 the shank is also made tapered but

round, both forms being adapted for use in connection with my improved doubly-shouldered post or pin, the angular form preventing the turning of the post after the shank has once been set in place in the bushing 31, while the round form is peculiarly adapted to the screw-threaded form of post 3 seen in said Fig. 6 and to a circular bushing instead of the square bushing shown in Figs. 5 and 8.

It will be seen from the above description that the principal feature of my invention resides in preventing the splitting of the root, and the ready accessibility to the pulp or nerve canal that may be easily reached by simply removing the screw 29 to release the crown or cap 2, and then removing the screw 27 so that the improved doubly-shouldered post can be withdrawn from the upper end of said pulp or nerve canal. The crown can be just as readily replaced by the reverse handling of said post and screws.

I claim:—

1. In combination, a dental crown or cap, a tooth root, a fastening or coupling intervening said crown and root and comprising a vertical post having a body-portion adapted to removably-extend into the pulp-canal of the root, a doubly-shouldered head or flange on said body-portion adapted to removably seat in a shouldered recess made in the upper end of said pulp-canal, a vertical shank on said head adapted to engage a pit provided in the bottom of the crown, and means in the crown adapted to removably-fasten it to said shank in firm, upright position on the top of the root.

2. In combination, a dental crown or cap, a tooth root, a fastening or coupling intervening said crown and root and comprising a vertical post having a pointed body-portion adapted to removably-engage the pulp-canal of the root, a doubly-shouldered head or flange on said body-portion adapted to partially and removably seat in a shouldered cavity made in the upper end of the pulp-canal, a vertical shank surrounding said head and adapted to engage a pit provided in the bottom of the crown, a bushing in the crown adapted to engage said shank, and a transverse screw inserted into the crown from its lingual side and adapted to engage the said shank for removably-fastening the crown in supported-position on the top or finished table of said root.

3. In combination, a dental crown or cap, a tooth root, a vertical doubly-shouldered post or pin adapted to removably-engage the pulp-canal in the tooth root, a doubly-shouldered and grooved seat in the upper end of said pulp-canal, a flanged metal box or bushing fitting within said doubly-shouldered and grooved seat and adapted to contain the shouldered-portion of the post, a lateral lug on said doubly-shouldered por-

tion of the post adapted to engage a notch made in the countersunk upper portion of the box or bushing and to receive a vertical fastening-screw, an upright shank on the post, a vertical box or bushing in the

5 crown to engage said shank and provided with a lateral threaded box or lining, and a

countersunk screw in said lateral lining for removably-fastening or mounting the crown on the said shank and the root top.

WILLIAM E. CHESTER.
